(57) **CLAIM**

The ornamental design for an undergarment, as shown and described.

DESCRIPTION

FIG. 1 is a front right perspective view of an undergarment my new design in an in-use configuration;
FIG. 2 is a front left perspective view thereof;
FIG. 3 is a rear right perspective view thereof;
FIG. 4 is a rear left perspective view thereof;
FIG. 5 is a front right perspective view of the undergarment of FIGS. 1-4 in the in-use configuration shown inside out illustrating the interior thereof;
FIG. 6 is a front left perspective view thereof;
FIG. 7 is a rear thereof;
FIG. 8 is a bottom left perspective view thereof;
FIG. 9 is a bottom right perspective view thereof;
FIG. 10 is a bottom view thereof;
FIG. 11 is a front view of the undergarment of FIGS. 1-4 in a flat configuration shown inside out illustrating the interior thereof; and,
FIG. 12 is a rear view thereof.

The uneven-length broken lines and unshaded regions depicting the remainder of the undergarment represent features which form no part of the claimed design. The even-length broken lines immediately adjacent to the shaded region represents the appearance of environmental stitching. The even-length broken lines, including angled even-length broken lines, shown in the environment of a leg band represents the appearance of environmental stitching and form no part of the claimed design.

1 Claim, 12 Drawing Sheets
